MOP HOLDER AND WRINGER

Edward C. Bakemeier, near Indianapolis, Ind.

Application April 15, 1940, Serial No. 329,707

6 Claims. (Cl. 15—120)

This invention relates to hand mops, particularly for scrubbing floors, but also adapted for use elsewhere as may be desired.

A principal object of the invention is to provide a mopping element of flexible cords which will be folded double in use but elongated to a single ply for wringing without requiring the user to stoop over or touch the mop with his hands.

A further object is to provide a durable and inexpensive article which is easy to operate by inexperienced persons.

The object also is to provide a cord mopping element which will not tangle and bunch in use and to improve the details of the handle and attachment of the mopping element thereto.

I accomplish the above and other objects which will hereinafter appear, by the means illustrated in the accompanying drawing, in which

Fig. 1 is a view in side elevation of my improved mop and handle in position for mopping use, showing portion broken away and in partial section to better illustrate otherwise obscured parts;

Fig. 2 is a like view with the parts in relative positions with the mopping element in single ply elongation at the end of a wringing operation, with the middle portion of the mopping element broken away;

Fig. 3 is a top plan view on a larger scale of the device as seen looking at the cap at the top end of the handle;

Fig. 4 is an enlarged detail of the handle and cap at its end in partial section of the cap; and

Fig. 5 is an enlarged detail of the sliding sleeve partially in section, showing particularly the means for connecting the mopping element thereto.

Like characters of reference indicate like parts in the several views in the drawing.

A handle 6 is preferably a long cylinder of wood, but may be of other material. Attached to its lower end by a bayonet joint in which a channel is entered by a pin 7, is a sleeve 8, having two annular channels in the lower one of which a wire band 9 is seated which binds the ends of a series of flexible cords forming the mopping element 10 to the sleeve. The end of the sleeve is preferably hemispherical against which end the ends of the cords 10 are laid and there secured by tying or stitching them together.

A coil at the small end of a spirally wound tapering spring coil 11 is laid and fastened in the upper annular channel of the sleeve 8 as shown in Fig. 1.

The upper end of the handle 6 is reduced in

diameter as shown in Fig. 4, and an annular channel is formed in the reduced portion. A sleeve 12 telescopes over the reduced portion of the handle 6 and is rotatably retained there by the set screw 13. The outer end of the sleeve 12 is integral with an enlarged cap 14, which functions as a hand-hold in the operation of the mop as will be hereinafter described.

The handle 6 is formed with a longitudinal channel 15 extending from the lower end, for a major portion of the length of the handle, and communicates with a spiral extension 16 of several turns with a relatively long pitch.

Mounted on the handle 15 is a metal sleeve 17 of sufficient length to serve as a hand-hold. Formed in the inner surface is a seat in which a bearing ball 18 is seated. This ball enters the channel 15, causing the handle and sleeve to rotate together, but when the sleeve is raised, causing the ball to enter the spiral groove 16, the handle 6 will be rotated when the sleeve is held to keep the sleeve from turning. The member 19 is a covering of rubber for the metal sleeve 17 to increase the grip and the comfort to the hand in grasping the sleeve.

A mop head 20, preferably of wood, is removably secured to the lower end of the sleeve 17 by a bayonet joint comprising a suitable channel 21 and lug 22 so assembled that the head 20 will rotate with the sleeve and is removed by turning the head in a reverse direction. This head 20 has an outside annular groove in which the upper ends of the cord mopping member 10 are laid and secured by a wire 24. The upper end of the spring 11 is secured to the under side of the head 20, here shown by a staple 25, Fig. 5.

The operation of my invention is as follows: With the parts in the position shown in Fig. 1, the cords of the mopping element 10 are folded double and the device is ready for use as a mop. To wring the mop, the operator grasps the cap 14 with one hand and the sleeve 17 with the other hand. The sleeve 17 is pulled upwardly to the end of the straight channel 15 which expands the spring 11 as shown in Fig. 2. Then by a further outer travel of the sleeve 17, the handle 6 is caused to rotate by the travel of the ball 18 in the spiral channel 16, thereby twisting the cords of the mopping element 10 around the spring and handle. When the sleeve is moved downwardly to the straight channel 15 and along it, the movement is assisted by the spring 11 which normally retracts to the nested position shown in Fig. 1.

To keep the cords 10 from tangling and bunching they are preferably tied together part way

in adjacent pairs by ties 27 as shown in Fig. 1. While I have herein shown and described my invention in the one particular form, it is obvious that structural changes may be made without departing from the spirit of the invention and I, therefore, do not desire to be limited to that precise form beyond the limitations as may be imposed by the following claims.

I claim:

10. 1. In a mop, a handle, a sleeve slidingly mounted on the handle, a mop head terminating the lower end of the sleeve, a second sleeve secured to the lower end of the handle, a flexible relatively long mopping member having one end secured to the mop head and its other end secured to the second sleeve and a spirally wound spring surrounding the handle and secured to the mop head and to the second sleeve, the attachment of the mopping member to the first sleeve being 20 above the place of attachment of the spring to the first sleeve.
2. In a mop, a long cylindrical handle, a cap swiveled to the upper end of the handle, a sleeve slidingly mounted on the handle, a mop head 25 secured to the sleeve, a second sleeve secured to the lower end of the handle, a flexible relatively long mopping member having one end secured to the mop head and its other end secured to the second sleeve, said handle having a straight 30 groove extending from its lower end longitudinally of the handle for a distance approximately of half the length of the mopping member and said straight groove having a spiral extension of several turns with a relatively long pitch and 35 said sliding sleeve having a member entering the groove in the handle.
3. In a mop, a long cylindrical handle, a cap swiveled to the upper end of the handle, a sleeve slidingly mounted on the handle, a mop head 40 secured to the sleeve, a second sleeve secured to the lower end of the handle, a flexible relatively long mopping member having one end secured to the mop head and its other end secured to the second sleeve, said handle having a straight 45 groove extending from its lower end longitudinally of the handle for a distance approximately of half the length of the mopping member and said straight groove having a spiral extension of several turns with a relatively long pitch and said 50 sliding sleeve having a member entering the groove in the handle, and a spirally wound spring-coil secured to the mop head and to the second sleeve surrounding the handle.

4. In a mop, a handle, a sleeve slidingly mounted on the handle, a mop head terminating the lower end of the sleeve, a second sleeve secured to the lower end of the handle, a flexible relatively long mopping member having one end secured to the mop head and its other end secured to the second sleeve and a spirally wound spring surrounding the handle and secured to the mop head and to the second sleeve, the attachment of the mopping member to the first 10 sleeve being above the place of attachment of the spring to the first sleeve, said spring being frusto-conical in shape and normally longitudinally contracted to a nested position.

5. In a mop, a handle, a sleeve slidingly mounted on the handle to permit reciprocation longitudinally of and revolution about the handle, a second sleeve mounted in relatively fixed position on the lower end of the handle, a mop member surrounding the lower portion of the handle 20 and interconnected by its upper and lower end portions respectively to said sliding and said fixed sleeves, and a spiral spring normally longitudinally contracted surrounding said handle within said mop member and having its ends secured to 25 said two sleeves, whereby said sliding sleeve may be lifted and revolved about the handle to stretch out said mop member and the spring to wrap the mop member around the spring for wringing purposes.

6. In a mop, a handle, a sleeve slidingly mounted on the handle to permit reciprocation longitudinally of and revolution about the handle, a second sleeve mounted in relatively fixed position on the lower end of the handle, a mop member surrounding the lower portion of the handle and interconnected by its upper and lower end portions respectively to said sliding and said fixed sleeves, and a spiral spring normally longitudinally contracted surrounding said handle within 40 said mop member and between said two sleeves, whereby said sliding sleeve may be lifted and revolved about the handle to stretch out said mop member and the spring to wrap the mop member around the spring for wringing purposes, said 45 spring being frusto-conical in nature with its larger diameter and fixed to said sliding sleeve and its smaller diameter end fixed to said fixed sleeve.

EDWARD C. BAKEMEIER. 50
